UNITED STATES PATENT OFFICE.

ARLINGTON H. MOORE, OF DAYTON, OHIO.

FUME GENERATOR FOR BATHS.

Application filed August 16, 1920. Serial No. 403,939.

To all whom it may concern:

Be it known that I, ARLINGTON H. MOORE, a citizen of the United States, residing at Dayton, in the county of Montgomery and State of Ohio, have invented certain new and useful Improvements in Fume Generator for Baths, of which the following is a specification.

This invention relates to vapor generators, and more particularly to an apparatus for charging steam, air or gases with chemical vapors or impregnating such carrying medium with chemical or other substances.

The object of the invention is to simplify the structure as well as the means and mode of operation of such vaporizers or impregnating apparatuses, whereby they will not only be cheapened in construction, but will be more efficient in use, positive in operation, automatic in action, easily operated and controlled, and unlikely to get out of repair.

A further object of the invention is to provide means for increasing the contact of the carrying medium whether the same be steam, air, or gases, with the chemical or material with which it is to be charged and for insuring the passage of the carrying medium to the body of charging material.

A further object of the invention is to provide improved concentrating or condensing means to which such a moisture is extracted from the charge medium, leaving the carrying medium more highly charged with the chemical or impregnated to a greater proportional degree.

A primary object of the invention is to provide a generator for medicinal vapor baths, wherein steam will be thoroughly saturated or impregnated with the medicinal materials, and thereafter tempered or cooled, and the moisture extracted before reaching the patient in the bath cabinet.

With the above primary and other incidental objects in view as will more fully appear in the specification, the invention consists of the features of construction, the parts and combinations thereof, and the mode of operation, or their equivalents as hereinafter described and set forth in the claims.

Referring to the drawings Fig. 1 is a side elevation of the assembled apparatus, the condenser or intensifier of which has been shown in section. Fig. 2 is a detail sectional

view of the generator chamber. Fig. 3 is a top plan view partly broken away of the diffusing diaphragm and agitator. Fig. 4 is a side elevation of the agitating means. Fig. 5 is a bottom plan view of the dome or top cap of the agitator.

Like parts are indicated by similar characters of reference throughout the several views.

In certain therapeutic treatments vapor baths are employed consisting of steam or in some instances, hot air, which has been highly charged with medicinal chemicals, drugs, or compounds. In the preparation of the mineral vapor or medicinal vapor baths, various materials are employed either independently or in combination, such as creosote, sulphur, salt, various oils, certain acids, and like materials. Heretofore, it has been the practice to conduct the carrying medium, that is, the air or steam, through a tortuous passage over pans or traps containing such materials. However, the mere surface contact of the carrying medium, with the impregnating material, does not take up the material in sufficient quantity or with sufficient rapidity. In order that the carrying medium may be more quickly charged to a greater degree of impregnation, the present apparatus has been designed.

In the drawing, 1 is the generating chamber, adapted to contain a quantity of the chemical or medicinal materials intermixed with a quantity of water or other fluid to be employed in the treatment. The chemical or medicinal material may be held in solution within the generating chamber, or it may be of a character insolvent in water or the other fluid which may be employed, with which it is merely intermixed and either held in state of suspension, therein, or in the form of a precipitate. Many of the materials employed for this purpose will be found to be insoluble and are maintained in a state of intermixture with the water or other fluid by constant agitation.

Beneath the generator 1 is shown a heating apparatus 2 in the present instance a gas burner, by which the contents of the generating chamber are subjected to boiling temperature. Located in the bottom of the generating chamber 1, and submerged in the contents thereof, is a dome shaped or conical compartment 3, having access openings 3' adjacent to the base thereof, which

communicate with a chamber of the generator 1. The fluid contents of the generator are thus free to circulate thru the compartment 3. Rising from the apex of the conical or domed compartment 3 is an upright tube 4, open at its upper end, but overhung by a dome or cap 5. The dome or cap 5 is supported upon radial arms 9 carried by a collar 7, surrounding the upper end of the upright tube 4. Supported upon the upright tube 4, beneath the cap or dome 5, and in spaced relation one with the other is a series of transverse perforated diaphragms or diffusing plates 6. These diaphragms or diffusing plates 6 are of a diameter substantially equal to the internal diameter of the generator 1, and are centrally perforated to fit upon the upright tube 4. They are separated one from the other by intervening spacer sleeves 18. The lowermost diaphragm or diffusing plate of the series rests upon a collar 8, secured upon the tube 4. There may be any number of these diffusing plates according to the character of the material, and the degree of diffusion or intermixture required. In the drawing, there has been shown but two diaphragms or diffusing plates 6. These diaphragms or diffusing plates may comprise woven wire screens or thin sheets of metal or other materials, having therein a plurality of small perforations. The material employed for these plates will depend somewhat upon the character of the chemicals or medicinal materials with which the vapors are to be charged. It will be at once apparent that certain metals might have a catalytic effect upon these medicinal materials, or the metal might be attacked by the chemicals or medicinal materials, with which the metallic vapors might combine to form injurious or undesirable combinations. Hence for use in relation with materials of certain characters, these diffusing diaphragms may be of glass, porcelain, composition, or phenolic condensation materials. The perforations of the various diaphragms or diffusing plates are preferably though not necessarily of different sizes, whereby the diffusion or breaking up of the vapors and intermixture of the chemical or medicinal vapors and the steam is more uniformly and progressively effected.

The contents of the generator 1 being subjected to heat from the burner 2 are caused to boil, thereby generating steam within the generator chamber 1, from the chemical charged water or other liquids. While the entire contents of the generator are caused to boil and generate steam, the contents of the agitating chamber 3 being more directly subjected to the heat of the burner 2, are caused to boil more violently, than that portion of the contents outside said agitating chamber. This causes the

contents of the chamber 3 to rise thru the vertical tube 4, and discharge over the top thereof, thus inducing a continuous current or circulation within the generating chamber. As the highly heated and agitated 70 contents of the chamber 3 are discharged upwardly thru the tube 4, the chamber 3 is constantly supplied with fluid thru the intercommunicating openings 3'. The highly heated and agitated liquid discharged upward thru the tube 4 carries with it a considerable quantity of the chemicals or medicinal materials, which overflowing the top 75 of the tube 4 are deposited upon the diaphragms or diffusing plates 6, draining 80 backward therefrom thru the perforations of the plates into the lower portion of the generating chamber 1. During this process, the agitated liquid is broken up into very 85 small portions or fine streams, or in some instances in drops or globules, which drip from the diaphragms or diffusing plates 6. The descending charged liquid draining from the diaphragms or diffusing plates 6, 90 meet or intermingle with the steam and vapors arising from the main body of the liquid in the generating chamber. This steam and vapor generated by the boiling of the main body of chemically or medicinally charged water or other liquid is, of 95 course, charged to some extent with such chemicals or medicinal materials. However, in the passage of this body of vapors or steam thru the perforations of the diaphragms or diffusing plates 6, meeting and 100 mingling in such passage with the subdivided body of charged liquid, becomes further impregnated or charged to a much higher degree with such chemicals or medicinal materials. It will be noted that the 105 rising vapors or steam from the main body of the liquid and the highly charged and heated liquid draining from the diaphragms or diffusing plates, meet and pass in opposite direction within the generator. Moreover there will always be more or less of the liquid adhering to the diaphragms and diffusing plates thru which the steam and vapors must pass. The constant discharge 110 of the heated liquid, highly charged with chemicals or medicinal materials, over the diaphragms or diffusing plates 6 leaves upon such plates or diaphragms a more or less concentrated solution or deposit of such chemicals, and medicinal materials, with 115 which the rising vapors and steam are brought into direct contact. By this means the steam and vapor is caused to become highly saturated with the chemical or medicinal material before passing from the 120 generator chamber.

The charged steam and vapors having passed upwardly thru the descending drippings or draining of highly concentrated solution or charged liquid, and thence thru 125

the diaphragms or diffusing plates 6 absorbing in their passage a maximum amount of the chemical or medicinal emanations, leave the generator thru the conduit 10, 5 on its passage to the bath tub.

The conduit 10 leads to a condenser or intensifier 11 by which excess moisture is extracted from the steam leaving in the dry remaining steam a greater proportional 10 charge of the medicinal or chemical material. The condenser or intensifier 11 comprises a central chamber 12 divided into two compartments by a medial wall 13 extending in proximity to, but somewhat 15 spaced from the bottom of the compartment 12 to afford intercommunication between the respective compartments beneath the wall or baffle 13. Surrounding the chamber 12 is a water jacket 14, thru which cold 20 water is circulated for condensing purposes. The cold water supply enters the jacket at 15, and after circulating about the exterior of the chamber 12, is discharged thru the outlet 16. In the bottom of the compartment 25 12 is a drain 17 for the water of condensation. The charged steam entering the chamber 12 thru the conduit 10 is usually heated to a greater degree than can be conveniently 30 withstood by the patient. Within the chamber 12 this charged steam is somewhat cooled and the excessive moisture is deposited, the highly charged residue of steam passing beneath the medial wall 13 into the opposite compartment of the chamber 12, thence leaving the condenser or intensifier 11, thru the discharge conduit 20, which leads to the bath cabinet not shown 35 in the present drawing. This insures the medium being uniformly and thoroughly saturated with the medicinal or chemical material. 40

The purpose of the cap or dome 5 of the generator 1 is to intercept the charged liquid ejected from the vertical tube 4, and direct it downward upon the diaphragms or diffusing plates 6. The dome or cap 5 prevents enlarged globules of liquid from being entrained with the steam and vapor and carried from the generator thru the outlet conduit 10. The dome or cap 5 is preferably though not necessarily of greater diameter than the outlet conduit 10, and positioned concentrically therewith.

There is shown at one side of the generator 1, a filling tube 19, thru which the contents of the generator may be replenished.

From the above description, it will be apparent that there is thus provided a device of the character described possessing the particular features of advantage before enumerated as desirable, but which obviously is susceptible of modification in its form, proportions, detail construction and arrangement of parts without departing

from the principle involved or sacrificing any of its advantages.

While in order to comply with the statute the invention has been described in language more or less specific as to structural 70 features, it is to be understood that the invention is not limited to the specific details shown, but that the means and construction herein disclosed comprise but one of several modes of putting the invention into effect, 75 and the invention is therefore claimed in any of its forms or modifications within the legitimate and valid scope of the appended claims.

Having thus described my invention, I 80 claim:

1. In a fume generator, a boiler, a compartment within the boiler submerged in the liquid contents having an intercommunicating passage with the main chamber of the boiler for the circulation of liquid to be vaporized, a vertical discharge conduit extending from said submerged compartment to a point above the fluid level of the boiler, a foraminous baffle located within 90 the boiler intermediate the discharge outlet of the vertical conduit and the fluid level of the boiler thru which fluid discharged from the conduit descends and thru which the vapors generated within the 95 boiler arise, and an outlet conduit leading from the boiler above the level of the baffle.

2. In a fume generator of the character described, a boiler, an unobstructed foraminous baffle therein, a fume conduit leading from the boiler, above the level of the baffle, means for discharging chemically charged liquid upon the baffle, the vapors generated in said boiler below the level of the baffle being passed thru the foraminous 105 baffle in a direction opposite to the passage of the chemically charged liquid, substantially as specified.

3. In a fume generator, a generator for vapors to be charged, a foraminous wall intermediate the point of generation of the vapors and said conduit thru which the vapors are passed and means for discharging chemically charged liquid upon the foraminous wall during the passage of the 110 vapors therethru.

4. In a fume generator a generator for vapors to be charged, a discharge conduit for chemically charged liquid, and means for causing the liquid and vapors to pass 120 in opposite directions, the one thru the other at a point intermediate the point of generation of the vapors and the discharge conduit.

5. In a fume generator, a boiler having 125 an outlet opening at the top thereof, a diaphragm dividing the boiler into two intercommunicating compartments, a vertical conduit leading upwardly from the lower compartment within the boiler, an imper- 130

- forate baffle located in spaced relation above the upper end of the conduit, a second baffle located within the boiler below the level of the end of the conduit and above the liquid level of the boiler, said baffles being maintained clear and unobstructed for the distribution of liquid discharged thereon through said vertical pipe for intermixture with vapors arising within the boiler below the level of the baffles, whereby the vapors are brought into intimate contact with unvaporized liquid in their travel past the baffles to the outlet conduit, substantially as specified.
15. 6. In a fume generator, means for generating vapors to be charged, a vapor conduit leading from the generator means for discharging chemically charged liquid in sub-divided portions, and means for causing the vapors and subdivided portions at a point intermediate the point of generation of the vapors and the discharge conduit of liquid to meet and pass one thru the other in substantially opposite directions.
20. 7. In a fume generator, a generator for vapors to be charged a discharge conduit leading therefrom, and drip means for chemically charged liquid located above the point of generation of the vapors within the generator and below the level of the discharge conduit, the vapors to be charged being passed thru the dripping liquid to said discharge conduit substantially as specified.
25. 8. In a fume generator a fume discharge conduit leading therefrom, a steam generator, means for intermixing chemically charged liquid with the generated steam, comprising a foraminous plate located intermediate the liquid level and the discharge conduit of said generator upon which the chemically charged liquid is discharged and from which it is caused to drip, the generated steam being passed thru the dripping liquid to saturate the steam with such chemically charged liquid during its passage to said discharge conduit.
30. 9. In a fume generator, a steam generator, means for intermixing chemically charged liquid with such steam, a chamber having an inlet and outlet opening in the top thereof thru which the mixture of steam and chemically charged liquid is passed, a baffle in said chamber extending approximately to the bottom of the chamber but permitting the passage of the mixture of steam and chemically charged liquid from one side to the other thereof, and a jacket for cooling medium surrounding said chamber, substantially as specified.
35. 10. In a fume generator, means for intermixing steam and chemically charged liquid, and a condenser adapted to chill the intermixed steam and liquid to effect the deposit of excess moisture leaving the

remaining vapors proportionately more highly charged with the chemical.

11. In a fume generator, means for entraining chemically charged liquid in a steam current, and means for subsequently extracting excess moisture from the steam and entrained chemically charged liquid, substantially as specified. 70

12. The herein described method of charging vapors with chemicals and the like, comprising in evaporating the chemical mixture and simultaneously discharging through the vapors arising therefrom a quantity of the chemically charged mixture in sub-divided portions. 75

13. The herein described method of charging vapors with chemicals and the like consisting in evaporating the chemical mixture and simultaneously passing the resultant vapors and a quantity of the liquid mixture in sub-divided portions in opposite directions, the one through the other. 80

14. The herein process of generating vapors charged with chemicals or the like consisting in heating a mixture of the chemicals to release vapors thereof, and simultaneously dropping by gravity unvaporized portions of the mixture through the generated vapors. 90

15. The herein described process of chemically charging vapors consisting in heating the chemical mixture to generate steam passing the generated steam through a formating diaphragm and simultaneously discharging over said diaphragm an unvaporized portion of the mixture to cause the intermingling of the vaporized and unvaporized portions of the mixture substantially as specified. 95

16. The herein described method of producing medicinal vapors and the like, consisting in circulating a body of steam in intimate relation with a body of impregnating material whereby such material will become entrained with the steam and subsequently extracting a part of the moisture from the impregnated steam to relatively increase the strength of the vapors. 105

17. The herein described method of producing medicated vapors, consisting in circulating a carrier medium in intimate relation with the medicinal material whereby the carrier medium will be impregnated therewith and subsequently intensifying the mixture by extracting a portion of the carrier medium. 115

18. In a vapor generator, the combination with a steam supply means and means for charging the steam with impregnating media, of a condensing chamber through which the impregnated steam is conducted, whereby the excess moisture is extracted leaving an increased proportion of the impregnating media in the steam residue. 125

19. In a vapor generator, the combination 130

- with a steam supply means and means for charging the steam with impregnating media, of an intensifying chamber through which the impregnated steam is passed, and
- 5 a jacket for cooling media surrounding said chamber.
20. In a vapor generator, the combination with a steam supply means, and means for charging the steam with impregnating media, of a chamber through which the impregnated steam is passed having inlet and outlet openings in the top thereof and a pendant baffle wall intermediate the inlet and outlet openings, extending in proximity
- 10 to but spaced from the bottom of the chamber and a drain passage leading from the bottom of the chamber.

21. In a vapor generator, the combination with a steam supply means, and means for charging the steam with impregnating media, of a jacketed chamber divided vertically into two compartments intercommunicating at the bottom of the chamber, and inlet passage for the impregnated steam to one compartment and an outlet passage for the steam from the other compartment, cooling media being circulated through the jacket of said chamber.

In testimony whereof, I have hereunto set my hand this 9th day of July, A. D. 1920.
